UNITED STATES PATENT OFFICE.

ARTHUR H. MERRILL, OF CROMWELL, CONNECTICUT.

WATER-COOLER.

SPECIFICATION forming part of Letters Patent No. 242,214, dated May 31, 1881.

Application filed April 11, 1881. (No model.)

To all whom it may concern:

Be it known that I, ARTHUR H. MERRILL, of Cromwell, in the county of Middlesex and State of Connecticut, have invented a new Improvement in Water-Coolers; and I do hereby declare the following, when taken in connection with the accompanying drawing and the letters of reference marked thereon, to be a full, clear, and exact description of the same, which said drawing constitutes part of this specification, and represents a vertical central section.

This invention relates to an improvement in devices for containing ice-water, and from which water is drawn through a faucet, and commonly called "water-coolers." In the usual construction these are made double-walled, with a space between the walls, the inner wall of metal or coated with porcelain.

It is a well-known fact that water which stands in an earthen vessel is much better than that which stands in metal-lined; hence many coolers are made entirely of earthenware, but these are objectionable because of their great liability to breakage.

The object of this invention is to construct a cooler in which the water-holder shall be earthenware and yet protected both inside and out from breakage; and it consists in a water-cooler having an inner vessel or water-holder made from earthenware with an outer wall of metal, so as to leave a space between it and the earthen vessel, combined with a removable ice-holder constructed so that in placing ice in the water-holder the pieces of ice cannot come in contact with the water-holder, as more fully hereinafter described.

A is a vessel made of earthenware or similar

material in any desirable shape. This is set within a metal casing, B, of larger diameter, so as to leave an annular space, C, between the two, which space may be filled with charcoal or left without filling, as may be desired, but actual contact between the outer casing and the water-holder should be avoided.

The shape of the outer casing may be that of common water-coolers.

The usual faucet D is arranged to draw water from the cooler.

E is the ice-holder, which consists of a metal basket made from wire or perforated sheet-metal and arranged to be suspended by resting at the top, as at a, and should be provided with a bail, F, by which it can be readily lifted from the water-holder. This basket or ice-holder prevents any forcible contact of the ice with the walls of the water-holder, so that all liability to break the holder by dropping ice therein is prevented, and the cooler, in every respect equally as good as the best earthen coolers, is produced without any possible liability of breakage.

I do not wish to be understood as broadly claiming a detachable ice-holder for water-coolers and other purposes, for such I am aware is not new.

I claim—

A water-cooler consisting of the earthenware water-holder A, arranged and supported within an outer casing, B, combined with a detachable suspended ice-holder, E, substantially as described.

ARTHUR H. MERRILL.
